BULLET

Robert R. Clark, Chapel Hill, N. C.

Application March 27, 1941, Serial No. 385,550

1 Claim. (Cl. 102—88)

This invention relates generally to new and useful improvements in bullets and has for one of its important objects to provide a device of this character comprising a plurality of pivotally mounted, expansible wings which are normally in folded or retracted position during the flight of the projectile and which, upon impact of said projectile with an object, are caused to automatically swing to operative position.

Other objects of the invention are to provide a bullet of the character described which will be simple in construction, highly efficient and reliable and which may be produced at low cost.

The foregoing and other objects and advantages of the invention will become apparent from a study of the following specification, taken in connection with the accompanying drawing wherein like characters of reference designate corresponding parts throughout the several views, and wherein:

Figure 1 is a view in vertical longitudinal section through a bullet constructed in accordance with this invention.

Figure 2 is an elevational view of the projectile with the pivoted wings in expanded or open position.

Figure 3 is a detail view in top plan of the removable chamber plug and the elements mounted thereon.

Figure 4 is a cross sectional view, taken substantially on the line 4—4 of Figure 1.

Referring now to the drawing in detail, it will be seen that the embodiment of the invention which has been illustrated comprises a suitable case 1. An explosive charge 2 is provided in the rear portion of the case 1. A conventional cap 3 is provided in the case 1 rearwardly of the charge 2 for firing said charge.

Mounted in the case 1 and adapted to be expelled therefrom by the explosive charge 2 is a projectile which is designated generally at 4. The projectile 4 includes a nose 5 of suitable metal which protrudes forwardly from the case 1. The nose 5 is provided with a reduced rear end portion 6 having mounted thereon a ring 7 of comparatively soft, compressible and distortable metal. The ring 7 has formed therein a circumferential groove or channel 8 for the reception of a suitable lubricant for the bore of the gun. The channel 8 is also adapted to receive or accommodate the excess flow of metal when the ring 7 is compressed and distorted from the impact when the nose 5 strikes an object.

Mounted on the rear end portion of the ring 7 is a cylindrical chamber 9 in the form of a tube

of suitable metal. The rear end of the chamber 9 is closed by a removable plug 10.

Mounted centrally in the nose 5 and projecting therefrom into the chamber 9 is a metallic stem 11 or shank 11. The stem 11 is provided on its rear end with a head 12 which is adapted to eject the plug 10 from the chamber 9.

Mounted on the plug 10 in the chamber 9 is a substantially U-shaped connector or bail 13. The bight portion of the bail 13 has an opening therein which slidably accommodates the stem 11.

Also mounted on the plug 10 in the chamber 9 is a pair of substantially U-shaped brackets 14. Pivotally mounted on the brackets 14 are metallic wings 15. Coil springs 16 are provided in the chamber 9 for expanding the wings 15. The coil springs 16 are normally compressed between the folded wings 15 and bars or the like 17 which are mounted on the leg portions of the member 13.

20 In use, the projectile 4 is propelled from the gun in the usual manner when the charge 2 in the case 1 is exploded. When the nose 5 strikes an object said nose is mashed or flattened and the comparatively soft ring 7 is compressed and distorted by the impact. In this manner the stem 11 is caused to move rearwardly for ejecting the plug 10 from the rear end of the chamber 9. When the free ends of the pivoted wings 15 clear the rear end of the chamber 9 said wings are 25 swung outwardly to open position, as illustrated to advantage in Figure 2 of the drawing, and tear a large, jagged hole in the object struck as the bullet passes therethrough. The chamber 9 is provided with a frangible lining 18 of asbestos or other suitable fire resisting material.

It is believed that the many advantages of a bullet constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

45 What is claimed is:
 A bullet of the class described comprising a nose, said nose comprising a reduced rear end portion, a comparatively soft compressible, distortable ring mounted on said reduced end portion of the nose, said ring having a circumferential groove therein, a tubular chamber mounted on the ring and projecting rearwardly therefrom, a removable plug in the rear end portion of said chamber, a plurality of expansible wings pivotally mounted on the plug and engageable in the

chamber for retention thereby in folded position, a stem mounted longitudinally in the nose and projecting rearwardly therefrom into the chamber and engaged with the plug for ejecting said plug from the chamber, said stem being operable upon compression and distortion of the ring when the nose strikes an object, a substantially U-

shaped connector on the plug slidable on the stem, a head on one end of the stem for retaining the connector thereon, and springs in the chamber engaged with the wings for opening said wings when the plug is ejected from the chamber.

ROBERT R. CLARK.
